UNITED STATES PATENT OFFICE.

EDMUND E. BLAKE, OF SACO, AND WILLIAM H. GOLDSMITH, JR., OF BIDDEFORD, MAINE, ASSIGNEES, BY MESNE ASSIGNMENTS, TO SACO-PETTEE COMPANY, OF NEWTON, MASSACHUSETTS, A CORPORATION OF MASSACHUSETTS.

CASING FOR ROVING-FRAME MECHANISM.

1,080,042.

Specification of Letters Patent.

Patented Dec. 2, 1913.

Application filed December 17, 1909. Serial No. 533,510.

To all whom it may concern:

Be it known that we, EDMUND E. BLAKE, of Saco, and WILLIAM H. GOLDSMITH, Jr., of Biddeford, county of York, State of Maine, both citizens of the United States, have invented new and useful Improvements in Casings for Roving-Frame Mechanism, of which the following is a specification.

10 The gears and the driving mechanism, especially that at the head or driving end of roving frames, have heretofore been more or less exposed, no convenient provision having been made for covering it in.

15 Moreover while a casing had been provided for bobbin shafts it was a matter of some difficulty and time to remove it to make repairs and for general cleaning and operating purposes. When the gears and

20 driving mechanism are uncovered they collect lint and fly and also are apt to throw oil. They are liable to injury and are liable to injure careless operatives. If covered, however, provision should be made for easy

25 removal of the cover and the covers, etc., should allow for the rise and fall of the bobbin rail.

Our present invention is intended to obviate these difficulties and in its present form it consists in a gear box having a cover; the box supported by one end of the bolster rail and adapted to move with it; the cover being easily removable from the box without interfering in any way with the bearings in which the gears or shafts are carried and yet being held firmly in place so as to exclude dirt, etc. The cover preferably also carries sliding shields which slide with the bolster rail forming a reciprocating door co-operating with a corresponding shield or apron depending from the stationary roller beam to close in the mechanism under it.

Our invention will be understood by reference to the drawings in which—

Figure 1 is a front elevation of mechanism embodying our invention, the gears being omitted and the gear box being shown in vertical section on a plane in front of the bolster rail. Fig. 2 is a side elevation of the gear box, etc., the bolster rail and shield being shown in section and one of the bearings being removed, and Fig. 3 a plan.

A is the head of the machine containing the mechanism usually contained therein and having in addition a guideway or vertical track A¹ on which runs the rail guide A², the whole being counterbalanced by a weight (not shown) connected thereto by a chain a, this chain running over a suitable pulley (not shown) contained in the housing a¹. To the rail guide A² is bolted the gear box B containing gears B¹, B² and B³, shown in dotted lines in Fig. 3, mounted on shafts C and D.

B⁴ in Fig. 1 shows an opening in the rear of the box through which connection is made between gear B³ and the operating mechanism in the rear of the box.

The shafts C and D are mounted in bearings C¹, C², D¹, D², connected to the gear box by bolts c¹, c², d¹, d². Upon the gear box is also mounted the bolster rail E, the gear box for this purpose being provided with a bracket E¹ upon which one end of the rail is supported and to which it is attached by bolts e, bolts e¹ also being provided by which the bracket is attached to the gear box, and a bolt e² by which the rail is especially attached to the gear box.

The gear box has a cover F which is attached thereto by the bearing-attaching bolts c², d² which pass through the bearings and into the cover. It will be noted therefore that so far as the mechanism is at present described, to remove the cover of the gear box it is only necessary to remove these bolts c², d² which pass through it. The cover of the gear box then may be lifted off and the gears exposed without in any way interfering with their bearings. The cover F is provided with a groove in which the bolster rail sets when resting on the bracket E¹. In addition, however, to the cover F, we provide the stationary rail or roller beam G with what may be termed an apron or stationary shield g bolted thereto at g¹ and we provide the cover F with a bracket h to which is attached a slide plate H, this slide plate being arranged to rise and fall with the bolster rail, the gear box serving as a means of connecting the two and in so doing to slide against the apron g. It has a close or sliding contact therewith and if thought desirable (though this is not necessary), grooves may be provided to

receive the edges of the shield H to guide it in its vertical movement.

In the roving frame for which this structure is particularly intended certain mechanism is located below the roller beam G. This mechanism is not shown in the drawings and is not described as it is not essential in its detail to the present invention. By the means heretofore described, however, this mechanism is all inclosed within the shield and apron in such a manner that as the bolster rail together with the gears B¹, B², B³ and shafts C and D referred to, rises and falls in the ordinary operation of the machine, the part H also rises and falls, sliding over the surface of the apron g, always overlapping such apron and thus never exposing any of the mechanism back of it under the roller beam G to the dirt and fly which would otherwise reach it.

This invention while quite simple has proved of great value because it has made unnecessary a great deal of the cleaning which a roving frame otherwise constantly requires because of the amount of lint, dirt and fly which is always circulating around the machine and which because of the rapid movement of the parts is apt to be drawn in against the oily mechanism. The tendency of the neat workman to keep his machine clean tempts him to remove dirt, etc., while the machine is in motion and hence expose himself to accident. The closing up of all this mechanism in such a way as not to interfere with the working of the machine and at the same time to make it possible to remove the cover and shield by merely removing the bolts c², d² has proved a great improvement upon any former con-

struction of which we have knowledge. The removing of these parts does not in any way interfere with the operative part of the machine, but simply exposes it so that its operation may be watched and if necessary it then may be shut down and cleaned or otherwise attended to.

We have shown our invention as applied to one distinct part of a particular type of machine, but it is evident that its application is not necessarily confined to this use.

What we claim as our invention is:—

In a roving frame, in combination, a stationary roller beam, a stationary guideway, a rail guide coöperating with said guideway, a gear box secured to said guide, a reciprocating bolster rail secured to said gear box at the opposite side thereof from said guide, gears in said gear box coöperating with said rail, shafts for said gears, bearings for said shafts secured to said gear box, a cover for said gear box detachably secured to said bearings, and means for closing the space between said roller beam and bolster rail comprising a longitudinally extending apron depending from said beam and a shield carried by and detachable with said gear box cover and extending therefrom longitudinally of said rail, said apron and shield being in engagement in all positions of said rail and being slidable on one another in a direction transverse to their length.

EDMUND E. BLAKE.
